UNITED STATES PATENT OFFICE.

ALFRED BOUSFIELD, OF ST. JOHNSBURY, VERMONT, ASSIGNOR TO E. AND T. FAIRBANKS AND COMPANY, OF ST. JOHNSBURY, VERMONT, A CORPORATION OF VERMONT.

DESIGN FOR A WEIGHING SCALE.

Application filed November 14, 1925. Serial No. 15,417. Term of patent 14 years.

To all whom it may concern:

Be it known that I, ALFRED BOUSFIELD, a citizen of the United States of America, residing at St. Johnsbury, in the county of Caledonia and State of Vermont, have invented a new, original, and ornamental Design for Weighing Scales, of which the following is a specification, reference being had to the accompanying drawings, forming part thereof, and in which—

Figure 1 is a front elevation, and

Fig. 2 is a side elevation of a weighing scale, showing my new design.

I claim:—

The ornamental design for a weighing scale, as shown.

ALFRED BOUSFIELD.
